(57) **CLAIM**

We claim the ornamental design for a wheel hub, as shown and described.

DESCRIPTION

FIG. 1 is a rendered front-left perspective view of a wheel hub according to our design;

FIG. 2 is a rendered front-right perspective view of the design;

FIG. 3 is a rendered front view of the design;

FIG. 4 is a rendered rear view of the design;

FIG. 5 is a rendered left-side view of the design;

FIG. 6 is a rendered right-side view of the design;

FIG. 7 is a rendered top view of the design; and,

FIG. 8 is a rendered bottom view of the design.

The broken lines shown in the drawings are for illustrative purposes only and form no part of the claimed design.
